UNITED STATES PATENT OFFICE.

FREDERICH MAURER, OF PEORIA, ILLINOIS.

DESIGN FOR A CHIMNEY TOP OR CAP.

SPECIFICATION forming part of Design No. 19,823, dated May 6, 1890.

Application filed April 5, 1890. Serial No. 346,785. Term of patent 14 years.

To all whom it may concern:

Be it known that I, FREDERICH MAURER, of Peoria, in the county of Peoria and State of Illinois, have invented a new and original 5 Design for a Chimney-Top, of which the following is a full, clear, and exact description.

My invention relates to a design for a chimney top or cap, the essential features of which are the general configuration of said top and 10 its ornamentations.

Reference is to be had to the accompanying photograph, which forms part of this specification, and which represents a view in perspective of a chimney top or cap embodying 15 my new and original design.

The chimney top or cap A is essentially of rectangular configuration as viewed horizontally. Its base is ornamented by a substantially ogee molding b, and the upper configu-

ration of its sides c c and d d are essentially 20 of arched form. At angles formed by the meeting sides are pinnacle-shaped ornaments e e, and the sides are further ornamented in the shape of perforations therein, certain of which on two opposite sides c c have ornamental animal-like figures resembling lions 25 f f within them, while certain of the perforations in the other two opposite sides d d have ornamental star-like figures g g within them.

Having thus described my invention, I 30 claim as new and desire to secure by Letters Patent—

The design for a chimney top or cap herein shown and described.

FREDERICH MAURER.
